UNITED STATES PATENT OFFICE.

WILLIAM W. LASKER, OF BROOKLYN, NEW YORK, ASSIGNOR TO POWERS ACCOUNTING MACHINE CORPORATION, OF NEW YORK, N. Y., A CORPORATION OF DELAWARE.

CARD-REGISTRATION MECHANISM.

Application filed May 29, 1924. Serial No. 716,698.

To all whom it may concern:

Be it known that I, WILLIAM W. LASKER, a citizen of the United States, and a resident of Brooklyn, county of Kings, State of New York, have invented certain new and useful Improvements in Card-Registration Mechanism, of which the following is a specification.

The present invention relates to card control machines for tabulating, sorting, accounting or any other type of machine in which statistical data is assembled, and relates more particularly to the registration mechanism which locates each card in position with respect to the pin-box of the machine. In registration mechanisms employed in machines of the character outlined it frequently happens that a card becomes jammed or caught in the registration mechanism, and consequently, since the card feed is still in operation a number of cards will jam or buckle in the registration mechanism before the machine can be stopped, and after the machine has been stopped, crushed and damaged cards can only be removed from the mechanism with difficulty and considerable loss of time.

Some of the objects of the present invention are to provide an improved card registration mechanism; to provide means in a card registration mechanism whereby access can be readily had to the card passage in the mechanism in case a card fails to feed through the registration passage; to provide a card registration mechanism having a movable part whereby the mechanism can be opened and a card quickly removed from the mechanism; to provide a card registration mechanism whereby the loss of time caused by cards becoming caught in the mechanism is reduced to a minimum; and to provide other improvements as will hereinafter appear.

In the accompanying drawings, Fig. 1 represents a transverse section of a card registration mechanism embodying one form of the present invention; Fig. 2 represents a plan of the same; Fig. 3 represents a plan of one of the registration plates with a part removed therefrom; and Fig. 4 represents a plan of the part removed from the plate of Fig. 3.

Referring to the drawings, one form of the present invention comprises a card registration mechanism 10 formed of an upper plate

11 conforming generally to the shape of the cards used and a lower plate 12, the two plates 11 and 12 being suitably fastened together in a fixed manner by the use of studs 13 or like fastening means and are spaced apart a predetermined distance to provide a passage 14 into which the cards are fed successively to be positioned in operative relation to the pin-box which is employed to select the particular data punched in the card. The lower plate 12 is of substantially the same general shape as the upper plate 11 and has an angularly disposed lip 15 at the receiving end in juxtaposed relation to an angularly disposed lip 16 on the plate 11, also at the receiving end of the registration mechanism. These lips 15 and 16 diverge with respect to the passage 14 and thus form a converging guide for the cards which directs them into the passage 14. The two superposed plates 11 and 12 are each provided with perforations 17 and 18 corresponding in arrangement to the pins of the pin-box so that when the latter is lowered to perform a selecting operation the pins can pass freely through the top plate 11 and those pins which find openings in the card can pass freely through the lower plate 12. In the present construction the top plate 11 is of skeleton form and provides only a card guide surface of sufficient size to prevent the card from buckling when it is in position against the usual card stop which holds it momentarily in registering position in the passage 14.

For the purpose of gaining access to the passage 14 in case a card becomes caught in the registration mechanism through a misfeed, or any other reason, the plate 11 is provided with a section 20, here shown as removable, formed of a perforated part 21 and a strip 22 which interfits with the other section of the plate 11 to form in assembled condition the complete top plate heretofore described. In this instance the part 21 seats flush with the main part of the plate 11 by the provision of an extension flange 23, while the part 22 in assembled condition is a part of the lip 16.

For attaching the section 20 to its cooperating part, headed pins 24 are secured at opposite ends of the plate 11 and on the fixed portions of the lip 16, while the removable strip 22 carries two bifurcated latches 25 and 26 arranged to respectively engage beneath

the heads of the pins 24. These latches are 5
slidably mounted on the lip 16 by the pro-
vision of slots 27 and 28 and fixed pins 30
and 31, and are normally held in locking
engagement with the pins through the me-
dium of coiled springs 32 and 33 acting re-
spectively between the pins 31 and fixed
pins 34 and 35 of the latches. These latches
are each provided as here shown with end
lugs 36 and 37, by means of which they can
be manually drawn toward each other from
locking position so that the removable section
of the top plate can be taken out at will.

Under normal operating conditions the
section 20 is seated in place in the top plate
11 and the construction is such that the
usual plane surface is provided to bound
one side of the card passage 14. The spring
pressed latches 25 and 26 are now respec-
tively interlocked with the pins 24 and hold
the parts rigidly together. In case a card
becomes caught in the passage 14 the ma-
chine is stopped and by taking hold of the
lugs 36 and 37, the latches 25 and 26 are
25 withdrawn from locking position and the
section 20 then lifted out of the top plate
11 so that the card can be removed. While
in the present instance the section 20 is en-
tirely removable this is only by way of ex-
ample and is a preferred construction but
it is to be understood that the same result
might be obtained by various other arrange-
ments of the section and the term "remov-
able" is generic and used in a broad sense
35 to include a hinged or any movable part
of a registration mechanism which gives ac-
cess to the card passage.

While only a single form is shown in
which this invention may be embodied, it is
40 to be understood that the invention is not
limited to any specific construction, but
might be applied to various forms without
departing from the spirit of the invention
or the scope of the appended claims.

45 Having thus described my invention, I
claim:

1. A card registration mechanism hav-
ing one side thereof formed as a perforated
plate having a removable perforated section

for access to a card in said mechanism, said 50
section being arranged to be removed with-
out disturbing said plate.

2. In a device of the character stated, the
combination of a card registration mecha-
nism comprising two spaced fixed plates 55
forming a card passage, one of said plates
having a detachable perforated section for
access to a card in said passage, and means
for detachably securing said section to its
plate.

3. In a device of the character stated, the
combination of a card registration mecha-
nism comprising two spaced fixed plates
forming a card passage, one of said plates
having a removable section for access to a 65
card in said passage, and means including
a spring pressed latch for removably se-
curing said section to its plate.

4. In a device of the character stated, the
combination of a card registration mecha-
nism comprising two spaced fixed plates
forming a card passage, one of said plates
having a removable section for access to a 70
card in said passage, and means including
a plurality of spring pressed latches for re-
movably securing said section to its plate.

5. In a device of the character stated, the
combination of a card registration mecha-
nism comprising a top plate and a bottom
plate fixed in spaced relation to form a card 80
passage, a removable section in said top
plate for access to a card in said passage,
and means interlocking said section and top
plate whereby said section can be removed
at will.

6. In a device of the character stated, the
combination of a card registration mecha-
nism comprising a top plate and a bottom
plate fixed in spaced relation to form a card 90
passage, a movable section in said top plate
for access to a card in said passage, and
means for securing said section in place as
a part of said top plate.

Signed at Philadelphia, county of Phil-
adelphia, State of Pennsylvania, this 22nd 95
day of May, 1924.

WILLIAM W. LASKER.
